E. SØRENSEN.
DENTAL PARALLELOMETER.
APPLICATION FILED DEC. 20, 1918.

1,314,223.

Patented Aug. 26, 1919.

THE COLUMBIA PLANOGRAPH CO., WASHINGTON, D. C.

UNITED STATES PATENT OFFICE.

EMIL SØRENSEN, OF NEW YORK, N. Y., ASSIGNOR TO CERTUS PARALLELOMETER COMPANY, OF NEW YORK, N. Y., A CORPORATION OF NEW YORK.

DENTAL PARALLELOMETER.

1,314,223.

Specification of Letters Patent. Patented Aug. 26, 1919.

Application filed December 20, 1918. Serial No. 267,577.

To all whom it may concern:

Be it known that I, EMIL SØRENSEN, a citizen of Denmark, and a resident of New York city, in the county of Bronx and State 5 of New York, have invented certain new and useful Improvements in Dental Paralleometers, of which the following is a specification.

This invention relates to an apparatus of 10 novel construction designed more particularly for accurately fitting a dental bridge to a pair of spaced teeth. Dental bridges as now frequently constructed, are secured to the teeth in a removable manner, so that 15 they may be taken out whenever desired for the purpose of cleaning or sterilizing the bridge or gum. In order to effect this removable connection, the bridges are provided generally with a pair of prongs, that 20 engage a pair of sockets sunk into the fold- or other inlays with which the prepared cavities of the teeth are charged. In order to obtain an accurate fit and thus permit a ready removal and insertion of the bridge, 25 it is necessary that these sockets be secured in perfect parallelism with each other, which with the means now at hand, has been found to be a matter of considerable difficulty. By the apparatus which forms the subject matter 30 of this invention, this parallel fitting of the sockets can be performed in a simple, quick and accurate manner.

In the accompanying drawing,

Figure 1 is a vertical section of a paralleometer embodying the invention;

Fig. 2, a rear view;

Fig. 3, a plan;

Fig. 4, a horizontal section on line 4—4

Fig. 1;

Fig. 5 a longitudinal section of one of the work holders, and

Fig. 6, a perspective view of an example of one of the sockets.

The apparatus comprises a horizontal base 45 plate 1, mounted preferably upon rubber feet or buttons 2. From plate 1, rise a pair of posts 3, having opposed grooves or ways 4, and constituting the support for a vertically movable table 5. This table (which is 50 preferably arc-shaped, to resemble generally, the outline of a jaw), extends horizontally from an upright back or guide 6,

received by grooves 4, a bracket 7, serving to effect a firm connection between the table and its back. To rear side of back 6, is affixed, an upright back 8, engaged by a pinion 9, fast on a shaft 10, which turns in bearings 11 of posts 3, and is provided with a knurled head 12. It will be seen that by turning shaft 10, table 5 may be raised or 60 lowered along posts 3, so as to approach or recede from base plate 1. In order to limit the downward movement of the table, there is provided, an upright stop pin 13, passing adjustably through a sleeve 14, secured to back 6, and engaged by a clamp screw 15. This pin upon striking plate 1, will prevent the further descent of table 5, so that by raising or lowering the pin within its sleeve, the downward path of the table 70 may be correspondingly increased or diminished. To the forward arcuate edge of table 5 are adjustably secured, a plurality of holders for engagement with the sockets that are to be fitted into the teeth. Each 75 holder is shown to consist of an upright pin or spindle 16, engaged by a chuck 17, which is rigidly secured in a vertical position to the outer end of a horizontally disposed elongated plate or member 18. This member 80 is provided with a longitudinal slot 19 engaged by a clamp screw 20 tapped into one of a number of perforations 21, that extend along the curved edge of table 5. Members 18 overhang the edge of the table, so that 85 in this way, the chucks clear such edge, and so sustain their spindles 16 that the latter will project beyond and below the table in a true vertical direction, or in parallelism with each other. By slackening screws 20, the 90 holders may be slid further inward or outward in a longitudinal or approximately radial direction and they may likewise be oscillated laterally into greater or less proximity to each other, so that any two spindles 95 may be adjusted into any desired cooperative relation the spindles, however, maintaining their parallelism during all adjustments.

To the lower end of each spindle 16, is 100 adapted to be removably held one of the sockets or female members to be fitted into the teeth. With the embodiment illustrated, the lower end of each spindle is T shaped

in cross section to fit into a slotted socket 22 of the shape illustrated in Fig. 6. But the shape of the socket may be varied at pleasure, which would necessitate a corresponding 5 change in the shape of the spindle.

- Upon bed plate 1, is adapted to be mounted below table 5, a platen or support 23 upon which a cast or dental model 24 may be secured in a horizontal position. 10 The platen is removably held to bed plate 1 by dowel pins 25 entering corresponding openings of the latter. Along the periphery of platen 23 is formed a row of apertures 26, adapted for the reception of a plaster 15 Paris or similar binder by means of which the model may be affixed to the platen.

The apparatus constructed as described may be used in a variety of ways, depending on the particular work to be performed and 20 upon the option of the dentist. The following will serve as an example:

The teeth that are to serve as a bridge anchorage, are prepared in the mouth of the patient, and a cast of the whole or the 25 respective part of the jaw is made. This cast or replica is secured to platen 23 by means of an intervening layer of plaster Paris 27 which by partly entering apertures 26, effects a firm anchorage. 30 Table 5 is raised, a pair of sockets 22 is fitted upon a pair of spindles 16, and the spindles are so adjusted that the sockets are suspended directly above the teeth cavities within which they are to be seated. Table 5 is lowered to project the 35 sockets into such cavities, and a wax filling 28 is molded around the sockets, to fill out the cavities, and reproduce the contour of the teeth. The table is raised, the parts are 40 separated and the wax casting is reproduced in gold inlay, after which such inlay may be fitted into the teeth of the model and the sockets may be refitted, by the apparatus into the inlays to check up the work. Both 45 the inlay as well as the sockets are now adapted to be fitted accurately into the mouth of the patient.

It frequently happens that a bridge is to be anchored to more than two teeth, and it 50 is for this operation, that a greater number than two spindles should be carried by the table.

After a fit has been made on one model, it may be removed together with its platen 55 23, and a new model, together with a new platen be introduced, so that any number of models may be successively worked without necessitating the finishing up of one model before the installation of the next.

60 It will be seen that by the apparatus constructed as described, the sockets may be fitted to the teeth in a quick, simple and accurate manner, thus assuring a correct fit of the bridge.

65 Various changes may be made in the

details of the construction of my parallelometer, and mechanical equivalents may be substituted for one or more of the elements of my claims without departing from the spirit of the invention as outlined in such 70 claims.

I claim:

1. A parallelometer comprising a support for a dental model, a vertically movable table, a plurality of horizontally disposed 75 plates mounted on such table to overhang the edge of such table, means on such table for securing said plates to such table in a manner to permit a linear and arcuate adjustment of such plates on such table and longitudinally adjustable bridge-socket holders carried by said plates.

2. A parallelometer comprising a support for a dental model, a vertically movable table, a plurality of horizontally disposed 85 plates mounted on such table to overhang the edge of such table, means on such table for securing said plates to such table in a manner to permit a linear and arcuate adjustment of such plates on such table and 90 bridge-socket holders carried by said plates.

3. A parallelometer comprising a support for a dental model, a vertically movable table, a plurality of members overhanging said table, means for adjustably securing 95 said members to said table, and a plurality of bridge-socket holders carried by said members.

4. A parallelometer comprising a support for a dental model, a vertically movable 100 table having apertures, a plurality of members overhanging said table, said members having slots, bolts that engage said apertures and slots, chucks carried by the members, and spindles carried by the chucks. 105

5. A parallelometer comprising a support for a dental model, a table, means for vertically moving said table, a plurality of bridge-socket holders adjustably secured to the table, and an adjustable stop controlling 110 the movement of the table toward said support.

6. A parallelometer comprising a base plate, a platen adapted to support a dental model, coöperating devices on the base plate 115 and platen whereby the platen is secured to the base plate in a predetermined position, a vertically movable table, and a plurality of adjustable bridge-socket holders carried by said table. 120

7. A parallelometer comprising a base plate, a platen having apertures adapted to anchor a dental model, coöperating devices on the base plate and platen whereby the platen is secured to the base plate in a pre-determined position, a vertically movable table located above the platen, and a plurality of bridge-socket holders carried by said table. 125

8. A parallelometer comprising a pair of 130

grooved uprights, a table, a guide on said table engaging said uprights, means for setting said table along said uprights, and a plurality of adjustable bridge-socket holders carried by the table.

9. A parallelogrometer comprising a base plate, a platen, means for removably secur-

ing said platen to said plate, means for removably securing a dental model to the platen, a vertically movable table above the 10 platen, and a plurality of bridge-socket holders adjustably secured to the table.

EMIL SØRENSEN.
